UNITED STATES PATENT OFFICE.

FREDERICK W. WINTER, OF PITTSBURGH, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,216,037.

Specification of Letters Patent. Patented Feb. 13, 1917.

Application filed February 13, 1915. Serial No. 7,949.

To all whom it may concern:

Be it known that I, FREDERICK W. WINTER, a resident of Pittsburgh, in the county of Allegheny and State of Pennsylvania, have invented a new and useful Improvement in Garment-Stays, of which the following is a specification.

This invention relates to garment stays or stiffeners and particularly those made of wire bent back and forth from edge to edge of the stay to form a series of alternately disposed loops or eyes lying along the opposite edges of the stay and united by transversely extending portions or crossings. In stays of this kind the resistance to edgewise bending is due largely to the wire in the closed ends of the eyes or loops, which is subjected to bending stresses, while flatwise bending is resisted largely by the torsional effect produced in the wire of the transverse portions or crossings.

The object of the present invention is to provide a stay of this class which is stiffer and more resilient than such stays as heretofore constructed, which may have a greater ability to resist flatwise bending in one direction than in the other, and which includes a longer length of wire in a stay of given dimensions than prior stays, so that bending strains are better distributed over a greater length of wire, and the wear, the liability of crystallization and the production of a permanent set upon short bends are correspondingly reduced.

The invention comprises the stay herein-after described and claimed.

In the drawings, Figure 1 represents a plan view of one form of stay embodying the invention; Fig. 2 is a plan view of a modification thereof; Fig. 3 is a cross section on the line 3—3, Figs. 1 and 2; Fig. 4 is an edge view of the stay shown in Fig. 1; Fig. 5 is a plan view of another form of stay embodying the invention; and Fig. 6 is a cross section thereof on the line 6—6, Fig. 5.

The stay shown in Figs. 1 and 2 of the drawings is formed of a wire or wires 1 bent back and forth from edge to edge of the stay to form a series of alternately disposed loops or eyes 2 lying along opposite edges of the stay and united by a series of transversely extending portions or crossings. These crossings may lie at an angle to a line normal to the length of the stay, as

shown in Fig. 1, or all or a part of said crossings may be normal to the length of the stay. Fig. 2 shows a stay in which half of the crossings are inclined and half are normal to the length of the stay. In both Figs. 1 and 2 the crossings are arranged in two alternating groups, marked 3 and 4 respectively, which are united to form successive loops or eyes along each edge of the stay, adjacent loops preferably overlapping each other slightly, as at 5, so that the several loops mutually support each other and thereby strengthen the stay and increase its resistance to bending, especially in the flatwise direction, while in edgewise bending the overlapping loops slide past each other.

In the present stay the resistance to bending, or in other words, the stiffness of the stay, is increased by bending or deflecting certain transverse or crossing portions out of the general plane of the stay as a whole, in such a manner that each bent section is in the form of an arch, as shown in Fig. 3 or 5. This may be carried out to any suitable degree. For example, in Figs. 1 and 2, only one group of alternate crossings, marked 4, is bent out of the plane of the stay, the crossings 3 of the other group being left straight and lying in the general plane of the stay, so that the stay in end or cross sectional view resembles a hollow girder with one side arched and the other side flat, as in Fig. 3.

The stiffening effect against flatwise bending is due to the localization of the twisting stress in the bent crossings, to short portions of the wire near the ends of the crossings. In other words, when all of the crossings are straight and lie in the general plane of the stay, as in prior stays of this class, the full length of the crossing is subjected to torsion upon flatwise bending. In the present stay, however, the intermediate portion of certain crossings is bent or deflected out of the plane of the stay. Any twist or torsion exerted upon said crossing is effective about an axis through the end portions thereof, is largely localized in the wire at the opposite ends of said crossing and has much less effect on the middle bent portion thereof. By reducing the length of wire in the bent crossings subjected to torsion the effect is to stiffen the stay as a whole, especially as against flatwise bending, and at the same

time to increase its resiliency or ability to return to initial position after being subjected to flexure.

The unsymmetrical forms of the stay shown in Figs. 1, 2 and 3, also give the stay a greater ability to resist flatwise bending in one direction, than in the other, the stay being stiffer when bent in that direction in which the arched or bent crossings are on the concave side of the curve than when bent in the opposite direction. This is due to the fact that when the stay is bent flatwise so that the arched or bent crossings are on the concave side of the curve the tendency is to compress each arched crossing or, in other words, to decrease its radius of curvature. On the other hand, when the stay is bent flatwise so that the arched or bent crossings are on the convex side of the curve the tendency is to stretch or open them out. This feature is of particular value in garment stays of this kind, which usually are subjected more frequently to bending in one direction than in the other.

25 The overlapping of adjacent loops upon each other gives the stay a shingled appearance when viewed edgewise, as shown in Fig. 4. In the present stay the loops are tilted in opposite directions along opposite edges of the stay, so that the stay has the same appearance when viewed edgewise along either edge.

The invention can obviously be applied to stays of various types. For example, Fig. 5 shows a stay of the same general type shown in an application of Elbert L. Hyde for garment stay, filed July 21, 1914, Serial No. 852,258, and which consists of wire bent back and forth across the stay alternately from edge to edge thereof to form a series of loops or eyes ^{2b} connected by two alternate sets of transverse portions or crossings, marked ^{3b} and ^{4b} respectively. The crossings ^{3b} are substantially straight and extend from edge to edge of the stay in lines substantially normal to the length thereof, while the crossings ^{4b} are sinuous and include a longer length of wire than the crossings ^{3b}. This produces a longitudinally extending portion ⁶ in each loop or eye, said portions pointing in opposite directions along opposite edges of the stay, and each overlapping at its end the next adjacent loop or eye. In this form of stay the crossings ^{4b} are bent out of the general plane of the stay into arched form, as shown in Fig. 6, while the other crossings, marked ^{3b}, lie in the general flat plane of the stay. The effect is the same as in the prior forms described,

namely, an increase in the ability of the stay to withstand flatwise bending stresses, due to the localization of the twisting effect in the end portions of the alternate crossings ^{4b}. The unsymmetrical form of the stay also makes the stay more resistant to flatwise bending strains when the arched crossings ^{4b} are on the inside of the curve than when on the outside.

What I claim is:

1. A garment stay, comprising wire bent back and forth from edge to edge of the stay to form a series of loops or eyes lying along the edge of the stay and connected by transverse portions or crossings, some of said transverse portions or crossings being bent or deflected out of the general plane of the stay into substantially arched relation thereto, and others lying in the plane of the stay. 70

2. A garment stay, comprising wire bent back and forth from edge to edge of the stay to form a series of loops or eyes lying along the edges of the stay and connected by two groups of alternately disposed transverse portions or crossings, the crossings of one group being bent or deflected out of the general plane of the stay and into substantially arched relation thereto, and the crossings of the other group lying in another plane. 80

3. A garment stay, comprising wire bent back and forth from edge to edge of the stay to form a series of loops or eyes lying along the edges of the stay and connected by two groups of alternately disposed transverse portions or crossings, all of the crossings of one group being bent out of the general plane of the stay away from the same face thereof, and crossings of the other group lying substantially in the plane of the stay. 90

4. A garment stay, comprising wire bent back and forth from edge to edge of the stay to form a series of loops or eyes lying along the edges of the stay and connected by transverse portions or crossings, said loops or eyes being tilted out of the general plane of the stay and adjacent loops or eyes along each edge of the stay overlapping each other, the loops or eyes along opposite edges of the stay being tilted in opposite directions, and some of said crossings being bent or deflected out of the general plane of the stay away from the same face thereof. 100

In testimony whereof, I have hereunto set my hand.

FRED'K W. WINTER.
